UNITED STATES PATENT OFFICE.

CARL A. SEALANDER, OF CHICAGO, ILLINOIS.

PROCESS OF MAKING WALL-COVERING.

1,209,342.

Specification of Letters Patent. Patented Dec. 19, 1916.

Application filed August 23, 1916. Serial No. 116,471.

To all whom it may concern:

Be it known that I, CARL A. SEALANDER, a subject of the King of Sweden, residing at Chicago, in the county of Cook and State of Illinois, have invented certain new and useful Improvements in the Processes of Making Wall-Covering, of which the following is a specification.

This invention relates to improvements in the method or process of making a covering or lining for walls, and it consists in certain peculiarities of the construction, novel arrangement and operation of the parts thereof, and in the material employed, as well as in the novel steps practised in the production thereof.

The principal object of the invention is to provide a covering for walls in general, which shall be comparatively simple and inexpensive, highly sanitary, attractive in appearance, easily positioned on the wall in the customary or ordinary way.

While my invention is adapted for use as a covering for walls in general, yet it is more particularly intended to be employed as a covering for the walls of bath-rooms, and other walls which are likely to be subjected to splashing of water, and another important object of the invention, is to provide a wall covering which is made up in pieces or blocks, and which can be carried in stock and supplied to the trade as desired or upon demand.

A still further object of the invention, is to furnish a wall covering which is impervious to water and dampness and can be given a marbleized effect in various colors, or any other attractive design or graining effect.

Other objects and advantages of the invention will be disclosed in the subjoined description and explanation.

In the accompanying drawing which serves to illustrate the invention, Figure 1, is a face view of a piece of wall covering embodying the invention and Fig. 2, is a cross sectional view taken on line 2—2 of Fig. 1, looking in the direction indicated by the arrows.

Like numerals of reference refer to corresponding parts throughout the two views of the drawing.

The covering consists of a face plate 3, of transparent material, but by preference of glass, and a body 4, which may be of

any suitable composition or material, such as concrete, cement, or like material, but by preference of what is known to the trade, as ready mixed plaster, and between the face 3, and the body 4, a quantity of adhesive material 5, which may be of any suitable kind, but by preference is composed of white glue, and white enamel, in about equal parts, mixed with a sufficient quantity of plaster of Paris to make a pasty mass.

In the manufacture of my wall covering, I place a quantity of water into a vessel, and then place on the surface of the water a small quantity of powdered aluminum, which floats and spreads on the surface of the water. I then dip in or subject one side of a piece of glass or other transparent material, to the water and aluminum, and a portion of both will cling to, or coat the surface of the piece of glass or transparent material. I then apply in water colors to the coated glass, shading to give a graining or marbleizing effect. This shading is done by a brush and suitable coloring matter, preferably what is known to the trade, as Swedish black. I then place on said surface of the glass a coating or layer of the adhesive material, which is by preference composed of the ingredients above mentioned, and in about the quantities above specified. While this adhesive coat or layer is in a plastic state, I apply the composition composing the body 4, while it is in a plastic state or condition, and then permit the body composition and the adhesive compound to "set" or harden, in which operation the entire mass will be firmly secured to the surface of the glass on which the graining or marbleized effect has been produced.

It is obvious that the treated or coated surface of the glass can be embellished with any suitable design or designs, and that on account of the transparency of the glass such design, designs, graining or marbleizing effect will be presented to view, when the covering is placed on the wall.

As white glue and white enamel and plaster of Paris are used to produce the adhesive combination or mixture, it is evident that a white back-ground at the rear surface of the glass will be afforded, thus bringing out in bold relief the designs, graining, or marbleizing effect on the glass.

This covering being made up in pieces or blocks of any suitable size it is manifest that

it can be carried in stock and that it can be placed in position on the wall in the usual or customary manner.

By using the powdered aluminum in the water, as above stated, and by dipping the sheet or piece of glass in the water so as to immerse at least one surface of the glass, it is obvious that a quantity of the water and aluminum will adhere to the glass, and that 10 on removing the glass from the water and holding the glass in substantially a vertical position, the water and the aluminum carried thereby will gravitate downwardly in streaks or grain like effect thus indicating 15 the lines or positions to be touched up lightly with a brush and water colors of any desired kind or shade. The adhesive material is then applied to the thus coated surface of the glass and is, by preference, 20 pressed in the direction of the lines of the

graining thus blending the colors and giving a natural marble appearance.

By the employment of the aluminum a hard, deep, and quite natural effect will be produced.

Having thus fully described my invention, what I claim as new, and desire to secure by Letters Patent is—

The herein described method of making wall covering consisting in subjecting one 30 surface of a piece of glass to water and powdered aluminum, then placing on said surface a design or designs, then applying an adhesive in a plastic state to said surface, and then applying a body composition in a 35 plastic state to said adhesive.

CARL A. SEALANDER.
